PREFABRICATED BUILDING VENTILATION UNIT

Tadashi Hanaoka, Kawasaki, Isao Kaneko, Tokyo, and
Iwao Shiina, Yamato, Japan, assignors to Misawa
Homes Co., Ltd., Tokyo, Japan

Filed Nov. 6, 1972, Ser. No. 303,811

Claims priority, application Japan Sept. 19, 1972

Term of patent 14 years

Int. Cl. D25—02

U.S. Cl. D13—1 R

FIG. 1**FIG. 3****FIG. 2****FIG. 6****FIG. 4**FIG. 5

FIG. 7

FIG. 1 is a top plan view of a prefabricated building ventilation unit showing our new design;

FIG. 2 is a front elevational view thereof;

FIG. 3 is a right side elevational view thereof;

FIG. 4 is a bottom plan view thereof;

FIG. 5 is a rear elevational view thereof;

FIG. 6 is a cross sectional view on line VI—VI of FIG. 2 showing the wall to which the unit is attached in dashed lines for illustrative purposes; and

FIG. 7 is a perspective view thereof.

We claim:

The ornamental design for a prefabricated building ventilation unit, as shown and described.
